UNITED STATES PATENT OFFICE.

ADDISON N. CALKINS, OF QUINCY, ILLINOIS, ASSIGNOR TO ELECTRIC WHEEL COMPANY, OF QUINCY, ILLINOIS, A CORPORATION OF ILLINOIS,

TRACTOR.

Application filed March 25, 1925. Serial No. 18,088.

The invention relates to tractors of the type comprising, in combination with spaced rotary supporting members, an endless chain composed of separate sections or links coacting to restrain flexing in an upward direction as the chain travels over the ground, but permitting a bending or flexing of the chain around the supporting members.

The object of the invention generally stated is to produce a chain for such a tractor in which the link sections are operatively connected together in a novel and advantageous manner to produce between adjacent links a truss action operating to prevent flexing of the chain upwardly as it passes over the ground, but permitting relative pivotal movement between the sections as the chain passes around the supporting members.

A general object is to produce a chain having a link section of simple construction, of relatively light weight capable of withstanding long and severe usage, and capable of manufacture on an economical basis.

In the accompanying drawings there is shown a preferred embodiment of the invention, but it will be understood that various changes in the construction and arrangement set forth are contemplated within the scope of the invention as expressed in the appended claims.

Figure 1 of the drawings is a fragmentary side elevational view of the improved tractor with the axle of one of the supporting members in section.

Fig. 2 is a fragmentary horizontal section taken approximately in the plane of line 2-2 of Fig. 1.

Fig. 3 is a fragmentary inner plan view showing two link sections connected together.

Fig. 4 is an end view of the same.

Fig. 5 is a fragmentary vertical sectional view taken approximately in the plane of line 5-5 of Fig. 3.

Fig. 6 is a transverse section taken in the plane of line 6-6 of Fig. 5.

Fig. 7 is a perspective view of the major portion of one link section.

Fig. 8 is a perspective view showing another portion of the link section.

The tractor comprises generally a central frame member 10 elongated in form and providing bearings at opposite ends in which are journaled the axles 11 of two pairs of

rotary supporting members or wheels 12. The frame member is mounted substantially midway between its ends to turn on a shaft 13 upon which the tractor frame proper is supported in the usual way.

The endless belt or chain is composed of a plurality of similar sections each comprising a tread portion or shoe 14 generally rectangular in form with its greatest dimension extending laterally of the tractor. Rising

from this shoe approximately centrally thereof is an upstanding structure preferably formed integral with the shoe and comprising two pairs of arms 15 and 16 terminating at their inner ends in a pair of laterally spaced bearings 17 adapted to support a pivot bolt 18 a substantial distance above the shoe and approximately in the median plane thereof.

The outer ends of the arms 15 are formed integral with a bearing 19 at the forward edge of the shoe 14 and diverge slightly while inclining rearwardly and upwardly for connection with the bearings 17. The outer ends of the arms 16 are formed integral with laterally spaced bearings 20 at the rear edge of the shoe 14 and converge toward their inner ends for connection at such ends with the bearings 17.

At opposite side edges of the shoe are formed track portions 21, the forward ends of which are constructed to provide bearings 22 alined with the bearing 19, these track portions being preferably cored out as indicated at 23 (Fig. 7) to lessen the weight of the section. Suitable reinforcing ribs 24 may be provided on the inner face of the shoe as clearly indicated in Fig. 7.

The arrangement of the parts is such that the laterally spaced bearings 20 at the rear or trailing edge of the shoe are adapted to enter between the intermediate bearing 19 and alined bearings 22 at the forward edge of the next adjacent shoe, the two sections being pivotally connected together by a pivot pin 25 passing through the several alined bearings 19, 20 and 22. To hold the pivot pin 25 in place the bearings 22 have formed at their outer ends a pair of lugs 26 on opposite sides of the bearing aperture, which lugs are apertured to receive a retaining pin 27.

The tread portions of the chain sections being thus pivotally connected together, the inner end portions of the several link sections are operatively connected in a manner

110

such as to permit relative pivotal movement between the tread portions in one direction, but to prevent relative pivotal movement between the sections in the opposite direction 5 as the chain travels over the ground. For thus connecting the inner end portions of the link sections together each is provided with a tie member 28 having one end rigidly secured near the inner ends of the arms 15 and 16 and its other end extended forwardly beyond the link section for pivotal and sliding connection with the inner end portion of the next adjacent link section. For convenience in manufacture, and in order that 10 it may readily be replaced or renewed, I prefer to make each of the members 28 in the form of a separate casting. As herein shown it comprises an arm 29 having at its rear end a yoke portion 30 adapted to straddle the spaced bearings 17 and having side portions with vertically spaced apertures 31 and 32. The apertures 31 are adapted to receive the pivot bolt 18 at the outer side of the bearings 17, and the apertures 32 are 15 adapted to register with aligned bearings 33 formed in the inner link structure below the bearings 17, and to receive a pivot bolt 34 mounted in the bearings 33. The arm 29 carries at its extreme forward end a head 35 having an arcuate slot 36 therein, said head being of a width adapted to enter between the spaced bearings 17 of the next adjacent link section, as shown clearly in Fig. 5. The arm preferably curves outwardly slightly, the 20 arrangement being such that in the relative pivotal movement between adjacent link sections, as the latter pass around the rotary supports the heads 35 may pass through the yokes 30 of the next adjacent sections as 25 permitted by the movement of the pivot bolts 18 in the slots 36.

To guide the link sections around the rotary supporting members 12 the track portions 21 of each section are provided with 30 inwardly extending flanges 37 at the inner edges of the track portions; and to cause the link sections to adhere snugly to the peripheries of the supporting members as they pass around them, means is provided operating 35 to maintain the chain under tension. Thus the axle 11 for one pair of supporting members 12 is mounted in a movable bearing 38 slideable in a bearing box 39 at one end of the frame member 10. The latter has an 40 opening 40 therein at one end of which is mounted a screw 41 having an adjusting nut 42 thereon between which and the bearing 38 is interposed a coiled expansion spring 43, the latter passing through a suitable opening 45 in one side of the bearing box.

It will be seen that by the construction provided a rigid tread of substantial length is in effect produced as the chain travels over the ground, which tread is flexible in the opposite direction to permit the passage of the 50

chain around its rotary supports. In supporting the load the adjacent link sections coact to form in effect a truss of which the arms 15 and 16 of adjacent sections form the sides and the members 28 constitute the tie. 55 The chain thus possesses great strength and the construction is such that the parts are subjected to very little wear. In this connection it will be noted that the arcuate slot 36 in the head 35 is made of a width throughout the major portion of its length slightly greater than the diameter of the pivot bolt 18 so as to avoid friction between these parts.

I claim as my invention:

1. A tractor of the character described 80 comprising an endless chain having a series of link sections each including a tread portion, means pivotally connecting the tread portions in edge to edge relation, an inwardly extending structure rigid with each of said tread portions and having a pivot mounted therein near its inner end substantially in the median plane of the tread portion with a part having one end in the form of a yoke mounted on said pivot and its other end interfitting with the yoked end of the next adjacent part and having an elongated opening therein adapted to receive the pivot of the next adjacent section, the arrangement being such that said parts coact with the pivot bolts to restrain relative pivotal movement between the sections in one direction but permit a limited relative pivotal movement between the sections in the opposite direction. 95

2. A tractor having an endless chain composed of a series of link sections comprising tread portions pivotally connected together at their leading and trailing edges, a plurality of arms formed integral with the tread portion of each section and extending inwardly from its forward and rear edges toward the median plane of the tread portion, a connecting member rigid with the inner ends of said arms and extending forwardly therefrom, said member having an elongated opening in its forward end, and a pivot bolt carried by the inner ends of said arms with which the slotted end of the connecting member of the next adjacent link section is adapted to engage. 110

3. A tractor having an endless chain composed of a series of link sections comprising tread portions pivotally connected together at their leading and trailing edges, a plurality of arms formed integral with the tread portion of each section and extending inwardly from its forward and rear edges toward the median plane of the tread portion, a member rigid with the inner ends of said arms and extending forwardly therefrom, said member having an elongated opening in its forward end and a pivot bolt carried by the inner ends of said arms with which the slotted end of the connected mem- 120 125 130

- ber of the next adjacent link section is adapted to engage, said connecting member being formed separately from said arms and mounted on the pivot bolt carried thereby.
5. A tractor of the character described comprising an endless chain composed of a series of link sections with tread portions pivotally connected together, means supporting a pair of spaced bearings inwardly of the tread portion of each section approximately centrally of the tread portion, a pivot bolt mounted in said bearings, a connecting member mounted on said pivot bolt and extending forwardly for pivotal and sliding connection with the pivot bolt of the next adjacent section, and means operating to hold said connecting member against turning on its supporting pivot.
10. 5. A tractor of the character described comprising a plurality of link sections having tread portions pivotally connected together and each having a pair of laterally spaced bearings mounted inwardly of the tread portion substantially centrally thereof, a pivot bolt carried by said bearings, and a member having one end in the form of a yoke mounted on the pivot bolt of one section and adapted to straddle said spaced bearings and its other end adapted to enter between the spaced bearings of the adjacent section and having an elongated opening therein adapted to receive the pivot bolt of said adjacent section.
15. 6. A tractor of the character described comprising a plurality of link sections having tread portions pivotally connected together and each having a pair of laterally spaced bearings mounted inwardly of the tread portion substantially centrally thereof, a pivot bolt carried by said bearings, and a member having one end mounted on the pivot bolt of one section and its other
- end adapted to enter between the spaced bearings of the adjacent section and having an elongated opening therein adapted to receive the pivot bolt of said adjacent section, said member being held against rotation on its supporting pivot bolt.
20. 7. A tractor of the character described comprising a plurality of link sections having tread portions pivotally connected together and each having a bearing mounted on the tread portion substantially centrally thereof, a pivot carried by said bearing, and a member having one end mounted on said pivot and its other end on the pivot of the adjacent section, one end of said member being slotted to receive its pivot and the other end being in the form of a yoke to straddle the slotted end of the next adjacent member.
25. 8. A tractor of the character described comprising an endless chain composed of a series of link sections with tread portions pivotally connected together, means supporting a pair of spaced bearings inwardly of the tread portion of each section approximately centrally of the tread portion, a pivot bolt mounted in said bearings, a connecting member mounted on said pivot bolt and extending forwardly for pivotal and sliding connection with the pivot bolt of the next adjacent section, and means operating to hold said connecting member against turning on its supporting pivot, said pivotal and sliding connection including a slot in said connecting member of a width throughout the major portion of its length slightly greater than the diameter of the pivot bolt.
30. In testimony whereof, I have hereunto affixed my signature.
- ADDISON N. CALKINS.
